UNITED STATES PATENT OFFICE.

JOSEPH PATRICK KANE, OF NEWARK, OHIO.

TUBE-ROLLING MACHINE.

SPECIFICATION forming part of Letters Patent No. 739,424, dated September 22, 1903.

Application filed September 18, 1902. Serial No. 123,942. (No model.)

To all whom it may concern:

Be it known that I, JOSEPH PATRICK KANE, a citizen of the United States, residing at Newark, in the county of Licking and State of Ohio, have invented certain new and useful Improvements in Tube-Rolling Machines, of which the following is a specification.

In treating boiler-tubes it is the practice at present when it is desired to clean the tubes to cut them away from the flue-sheet and after they have been cleaned to weld a piece of tube to the old tube in order to make it the length necessary to fit in the boiler again. After the piece of tube has been welded on it is customary to reduce the place where it is welded by placing it when cold between two blocks having semicylindrical grooves and with a hammer strike one of the blocks. This process is liable to either break the weld or at least to injure it or the tube.

My invention is intended to take the place of swaging by percussion and substitute that of rolling, and thus reduce to a minimum the danger of breaking the weld or tube, as in the present practice, as well as reduce the cost of treating the tubes.

Additional advantages of my invention will appear hereinafter and by reference to the drawings, in which—

30 Figure 1 is a side view in elevation of my invention; Fig. 2 an end view, and Fig. 3, a detail view, of my improvement.

Referring to the drawings, in which similar reference characters indicate corresponding parts throughout the several views, A represents any suitably-constructed framework for my machine, having a table B at its front end.

C represents a shaft suitably journaled in the frame A and driven by any motor, (not shown,) D being a roller secured to said shaft.

E represents a platform mounted by means of a standard F over the table B, and G a lever fulcrumed on the floor and pivoted to the end of standard F to operate the platform, H being a coil-spring to depress the table when pressure on the lever G is relieved.

I represents a box secured in any suitable manner on the platform E, consisting of a base-plate J and uprights K. L represents 50 rolls journaled in the uprights K, their axes being parallel with the axes of roller D and

so arranged that all of the rolls will bear against the tube, it being understood that different-size boxes and differently-arranged rolls are necessary to be provided for treating the various sizes of tubes. The uprights are cut away in segments, as shown at M, to permit the rollers bearing against the tube, N representing the tube, and O the mandrel.

55 It will be clear from the above statement of the purpose of my invention and the description thereof that after the piece of tubing has been welded on the end of the tube N it is laid on the rolls L and the platform E raised by means of the lever G until the tube presses against the rotating roller D. Sufficient pressure is exerted through the lever G to roll the welded part to the diameter of the original tube, this being very quickly and effectively accomplished, and the tube is 70 ready for reinsertion into the boiler.

Having thus described my invention, what I claim is—

1. In a tube-rolling machine, in combination with a power-driven roller, a platform 75 arranged for vertical adjustment, a box secured to said platform, the ends of said box being cut away in segments, and rolls journaled in said ends, the journals of said rolls lying in a curve parallel with said segmental cut-away portion, substantially as shown and described.

2. A tube-rolling machine comprising in combination, a framework, a power-driven roller journaled therein, table, a platform secured to a standard passing through said table, a lever pivoted to said standard to elevate said platform, a coil-spring on said standard to depress the table, a box removably and replaceably secured to said platform, and rollers 85 journaled in said box having their centers on a segmental line, all of said rollers being adapted to press on the outer surface of a tube to roll it and reduce its diameter, substantially as shown and described. 95

In testimony whereof I hereto affix my signature in the presence of two witnesses.

JOSEPH PATRICK KANE.
